UNITED STATES PATENT OFFICE.

CHARLES R. CHENERY, OF BUFFALO, NEW YORK.

DESIGN FOR A BUTTER-PRESERVER.

50,093.

Specification for Design.

Patented Dec. 26, 1916.

Application filed October 3, 1916. Serial No. 123,593. Term of patent 14 years.

To all whom it may concern:

Be it known that I, CHARLES R. CHENERY, a citizen of the United States, residing at Buffalo, in the county of Erie and State of New York, have invented a new, original, and ornamental Design for Butter-Preservers, of which the following is a specification, reference being had to the accompanying drawing, forming part thereof.

The figure is a perspective view of a butter preserver showing my new design.

I claim:

The ornamental design for a butter preserver, as shown.

CHARLES R. CHENERY.
